UNITED STATES PATENT OFFICE.

WILLIAM D. GEROW AND FRANKLIN O. PRUSIA, OF DETROIT, MICHIGAN.

VEHICLE-BODY.

1,280,983.

Specification of Letters Patent.

Patented Oct. 8, 1918.

Application filed September 8, 1917. Serial No. 190,338.

To all whom it may concern:

Be it known that we, WILLIAM D. GEROW and FRANKLIN O. PRUSIA, both citizens of the United States of America, and both residing at Detroit, in the county of Wayne and State of Michigan, have invented certain new and useful Improvements in Vehicle-Bodies, of which the following is a specification, reference being had therein to the accompanying drawings.

The invention relates to metallic vehicle bodies and comprises the novel construction of metallic frame therefor, as hereinafter set forth.

15 In the drawings:

Figure 1 is a sectional side elevation of the vehicle body;

Fig. 2 is a sectional plan view thereof;

20 Figs. 3 and 4 are respectively a side elevation and horizontal section showing the frames for the door openings;

Figs. 5 and 6 are similar views showing the rear panel and supporting post;

25 Fig. 7 is a cross section showing one of the ribs or frame bars.

The essential feature of our improved construction is the formation of the frame of bars or strengthening ribs having a T-shaped cross section, the stem of the T being arranged intermediate and substantially parallel to the outer panel of the lining. As shown in Fig. 7, the T-shaped bars are preferably formed of a pair of U-bars A and B, having long legs or flanges C abutting 30 against and secured to each other and short flanges D at the outer edges thereof. The flanges C may be secured to each other by spot-welding or otherwise, while the flanges D form the securing means for attachment 35 to the outer and inner panels.

40 Compound bars formed as described may be variously fashioned according to the particular part of the frame formed thereby. Thus, as shown in Figs. 3 and 4, a bar E is bent longitudinally into a U-shape to form a supporting frame for the door-opening in the body; in Figs. 5 and 6 a bar F is bent into a curved form to impart the proper contour to the back panel; in Fig. 1 a bar 45 G is bent to form a border frame for the upper edge of the body,—and in the same manner the other parts of the body frame are suitably fashioned according to the contour desired.

In securing the various separately-formed bars to each other the central flanges C forming the stem of the T-shaped section may be overlapped and secured by spot-welding, riveting or in other suitable ways. The outer flanges D may be either overlapped or abutted, and the panel sheets of the body are then secured by spot-welding or otherwise to the flanges D. The arrangement of the flanges C intermediate the outer facing and the lining of the body is convenient, being out of the way, and these flanges, on account of their depth, will strongly brace and reinforce the transverse flanges forming the head of the T; also the bars of these sections may be more readily bent into the desired form and any wrinkling or irregularities produced by the bending will be in the flanges C and not in the comparatively narrow flanges D which are attached to the body facing. Thus the structure is one which is easily adapted to various shapes in body construction.

What we claim as our invention is:

1. In a metallic body for vehicles, a frame comprising a fashioned metallic bar of T-shaped cross-section, having the stem of the T arranged parallel to and between the outer and inner body sheets, and comparatively narrow flanges at the outer edges of the head of the T for attachment to said body sheets and conforming to the curvature thereof.

2. In a metallic body for vehicles, a frame comprising a curved metallic bar of T-shaped cross-section, being formed of a pair of U-shaped bars arranged side by side with contacting flanges secured to each other, the outer flanges of said U-shaped bar being of lesser depth than the contacting flanges.

3. In a metallic body for vehicles, a frame comprising a plurality of metallic bars of T-shaped cross-section and the stem of the T lying parallel to and intermediate the outer and inner sheets of the body, the opposite ends of the head of the T having comparatively narrow flanges for attachment to said sheets, said bars being joined to each other by overlapping the stem portions of the T.

In testimony whereof we affix our signatures.

WILLIAM D. GEROW.
FRANKLIN O. PRUSIA.
